(57) **CLAIM**

The ornamental design for a scanning laser ophthalmoscope, as shown and described.

DESCRIPTION

FIG. 1 is a side elevated view of a scanning laser ophthalmoscope showing my new design;

FIG. 2 is a rear elevated view of the scanning laser ophthalmoscope;

FIG. 3 is a front elevated view of the scanning laser ophthalmoscope;

FIG. 4 is a top plan view of the scanning laser ophthalmoscope;

FIG. 5 is a bottom plan view of the scanning laser ophthalmoscope; and,

FIG. 6 is a front perspective view of the scanning laser ophthalmoscope.
